(57) **CLAIM**

The ornamental design for battery packaging, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a bottom, left, back perspective view of a first embodiment of a battery packaging according to our new ornamental design;

FIG. 2 is a top, left, front perspective view thereof; and FIG. 3 is a front view thereof.

FIG. 4 is a bottom, left, back perspective view of a second embodiment of a battery packaging according to our new ornamental design;

FIG. 5 is a top, left, front perspective view thereof; and FIG. 6 is a front view thereof.

FIG. 7 is a bottom, left, back perspective view of a third embodiment of a battery packaging according to our new ornamental design;

FIG. 8 is a top, left, front perspective view thereof; and FIG. 9 is a front view thereof.

(Continued)

FIG. 10 is a bottom, left, back perspective view of a fourth embodiment of a battery packaging according to new ornamental design;

FIG. 11 is a top, left, front perspective view thereof; and FIG. 12 is a front view thereof.

FIG. 13 is a bottom, left, back perspective view of a fifth embodiment of a battery packaging according to new ornamental design;

FIG. 14 is a top, left, front perspective view thereof; and FIG. 15 is a front view thereof.

FIG. 16 a bottom, left, back perspective view of a sixth embodiment of a battery packaging according to new ornamental design;

FIG. 17 is a top, left, front perspective view thereof; and, FIG. 18 is a front view thereof.

The broken lines shown in the Figures represent environmental subject matter or boundaries of the battery packaging that form no part of the claimed design.

FIGS. 7-9 and 16-18 are shown with a symbolic break in the battery packaging width. The appearance of any portion of the article between the break lines forms no part of the claimed design.

FIGS. 2, 3, 5, 6, 8, 9, 11, 12, 14, 15, 17, and 18 are colored drawings.
